FIG. 1

FIG. 2

FIG. 3

FIG. 4

FIG. 1 is a perspective view from the bottom of a cup showing my new design;

FIG. 2 is a side elevational view;

FIG. 3 is a top plan view; and

FIG. 4 is a bottom plan view.

The characteristic feature of the design resides in the particular deformation of the bottom surface of the cup, as shown.

I claim:

The ornamental design for a cup, as shown and described.
